UNITED STATES PATENT OFFICE.

JAMES T. BRAYTON, OF CHICAGO, ILLINOIS; LIBBIE BRAYTON EXECUTRIX OF SAID
JAMES T. BRAYTON, DECEASED.

PROTECTIVE MASK FOR WORKMEN.

1,191,274.

Specification of Letters Patent. Patented July 18, 1916.

Application filed April 25, 1914. Serial No. 834,380.

To all whom it may concern:

Be it known that I, JAMES T. BRAYTON, a citizen of the United States, residing at Chicago, county of Cook, State of Illinois, 5 have invented a certain new and useful Improvement in Protective Masks for Workmen, and declare the following to be a full, clear, and exact description of the same, such as will enable others skilled in the art to 10 which it pertains to make and use the same, reference being had to the accompanying drawings, which form a part of this specification.

In many industries workmen are exposed 15 to injurious heat or light rays, to noxious gases, to dust or flying particles or missiles against which there has heretofore been no adequate safeguard for the workmen aside from heavy cumbersome devices like divers' 20 helmets which would naturally be used only in emergencies and not as an ordinary part of the apparel of the great multitude of workmen who need protection.

The object of my invention is to produce 25 a simple and novel device for protecting the face or parts thereof against light, heat, dust or flying missiles, which will permit the wearer to work in the presence of poisonous gases without being injured; which shall be 30 so light as not to be a burden but be entirely comfortable to the wearer; and which may be adjusted, when removing it, so as to leave the entire face of the wearer exposed.

The various features of novelty whereby 35 my invention is characterized will herein-after be pointed out with particularity in the claims; but for a full understanding of my invention and of its object and advantages, reference may be had to the following detailed description taken in connection with the accompanying drawings, wherein:

Figure 1 is a front elevation of a device arranged in accordance with a preferred form of my invention; Fig. 2 is a side view 5 of the head and neck of a person wearing the device illustrated in Fig. 1, portions being broken away for the sake of clearness; Fig. 3 is a view similar to Fig. 2, containing, however, an additional protective device; and 10 Fig. 4 is a view similar to Fig. 2 illustrating a simplified form of my invention.

Generally speaking, my invention may be said to comprise a novel protective mask whose structural details may be varied according to the particular use to which it is

to be put. For the sake of brevity, I have shown only a few simple constructions among which are embodied all of the essential features required to take care of the various conditions to which I have heretofore referred. It will of course be understood that where a device is to be used only for a particular purpose, it need not be made to embody features other than those necessary to fulfil the intended purpose. 60

Referring to Figs. 1 and 2, 1 represents a mask or shield large enough to cover the eyes, the nose and the cheek bones of the wearer, being preferably made of some light stiff material such as aluminum or tough 70 non-inflammable fiber bent or pressed into the proper shape. In the arrangement shown, the central portion, 2, of the mask or shield is shaped to extend over the nose and beneath the same to the vicinity of the upper lip, the part 2 projecting outwardly from the wings which extend over the eyes and cheek bones. The wing portions of the mask or shield are provided with suitable lenses, 3, which may be mounted in cups, 4, arranged upon outwardly pressed panels, 5, extending laterally from the sides of the nose piece. This arrangement permits the lenses to be held far enough away from the face to clear the eyelashes and at the same time prevent the heat of the lenses, in case they become hot, from affecting the eyes. The cups may be shaped in the manner described in my application for improvements in goggles executed of even date herewith, whereby the lenses are brought close together and the field of vision toward the front is not obscured. 85

The mask or shield is preferably hinged at its upper rear corners, as indicated at 6, to a suitable head band, 7, which may be a band of any suitable material having its ends fastened together by lacings, 8, which permit it to be adjusted about a head of any size. The parts are so proportioned that the mask or shield may either be swung down in the 100 position indicated in Fig. 2 or it may be swung upwardly about its hinged joints so as to lie on top of the head and out of the way.

Where the face of the workman is to be 105 protected against heat or light rays, only, the parts that I have just described are all that are necessary to give adequate protection. If the workman must work in the presence of poisonous gases or in a dusty atmos- 110

phere, additional protection is desirable. Thus the shield may be provided on the side next to the face with a cushion, preferably in the form of a pneumatic tube 9, so disposed that it will extend across the forehead of the wearer down over the cheeks and beneath the nose and thus form a reasonably tight seal between the mask or shield and the face. The pneumatic tube may be inflated in any suitable way as, for example, through a suitable nipple, 10, placed at any convenient point. In order to provide the workman with pure air, an air supply pipe 11, is led into the upper portion of the nose piece 2 so that fresh air may be supplied into the closed chamber between the shield or mask and the face. The air tube may be provided with regulating valves of any suitable type, there being in the illustration only a single valve, 12, within easy reach of the workman. The air tube is preferably arranged to pass up over the head and down the back where it may be attached to a suitable supply of compressed air carried in a receptacle on the workman's back or to a pipe leading to any suitable remote source of supply. It will be seen that with this arrangement air under any desired pressure may be supplied, so that the workman may breathe pure air regardless of the condition of the surrounding atmosphere. Furthermore, by supplying an excess of air, there will be a constant leakage of the same beneath the pneumatic cushion so that the face of the wearer will be kept cool and any poisonous gases or dust which might tend to enter through crevices left between the cushion and the face would be forced outwardly. Consequently, this simple arrangement permits a workman to enter a chamber completely filled with poisonous gases and to work in entire safety and comfort.

The discharge end, 11^a, of the air inlet pipe is preferably so arranged that it will cause the incoming air to travel laterally over the inner faces of the lenses and thus keep the lenses free from moisture. Where the device is to be used in the presence of dust, the outside of the lenses may be kept clean by providing the nose piece of the mask or shield with narrow slots, 13, disposed at the inner edges approximately in the plane of the lenses, so that some of the air will flow out across the lenses and blow away any dust which may accumulate thereon. With this addition the shield or mask permits the workman to be employed in an extremely dusty atmosphere without making it necessary for him to breathe dust or be in the least uncomfortable, and without fear that his vision will be obscured by reason of dust collecting on the lenses.

If desired, the head band 7 may be attached to or form part of a skull cap, 14, which will serve to cover the top of the head

of the wearer and, if desired, skirts, 14^a, of any desired material may extend down from the head band or skull cap so that, with the remainder of the parts, the entire head and face, except the mouth and a part of the chin 70 will be covered; the skirts being fastened under the chin with any suitable fastening devices as indicated at 15 and being tucked into the collar of the shirt, coat or blouse of the wearer. With this arrangement the 75 wearer is completely protected against dust and dirt.

In some lines of work, such as sand blasting, where steel shot are mixed with the sand, it is desirable that the lenses be protected against the rebounding shot and the sharp sand. For this use, an auxiliary apron may be provided as indicated at 16 in Fig. 3; this apron being of any suitable material, preferably flexible, and extending down 80 from the top of the mask or shield to a point below the lower edge of the same and preferably far enough down to permit its lower end to be tucked into the collar of the wearer. That portion of the apron just in front of 85 the lenses is made of gauze or slitted metal so that the apron contains a panel, 17, which does not obstruct the vision of the wearer but does protect the lenses against flying sand and shot. The lower portion of the 90 apron of course protects the mouth and chin of the wearer. The apron, 16, may be connected to the mask or shield in any suitable way; being, if desired, secured by means of 95 detachable fastenings which will permit it to 100 be attached and detached at will.

In Fig. 4 I have illustrated the simplest form of my invention in which the mask or shield 20 consists of a simple piece bent into the same general shape as the mask or shield heretofore-described, but having the bottom 105 of the nose piece, 21, open. The mask or shield is hinged to a head band, 22, at its upper rear corners and having an inwardly projecting lip, 23, at the center of the top, 110 which lip is adapted to rest upon a finger or projection, 24, on the front of the head band and thus prevent the mask or shield from swinging too far down. In other words, the mask or shield is supported entirely 115 from the hinges 25 and the lip 23, making no contact with the face of the wearer and therefore being cool and comfortable. When the mask or shield is not in use, it is simply swung back about its hinges and rests on 120 top of the head.

There is another feature of my invention which may be of considerable importance. The eyes of workmen exposed to intense light, such as workmen employed in electric 125 arc welding may be protected against the intense light by using properly colored glass in the lenses of the mask or shield. In the same way protection may be given to the eyes against injurious invisible light rays 130

by making the lenses of a properly prepared glass containing lead, bismuth, barium or some of their compounds. The mask or shield, including the skull cap and the curtains may be coated with suitable paints containing lead bismuth or barium and compounds so that the entire head and face of workmen engaged in electric welding or other work in which X-rays ultra-violet rays and other deleterious rays are given off will be completely protected. The same expedient may of course be adopted in connection with gloves and other clothing of the workman so that his entire body will be effectively shielded against injurious light rays.

It will of course be understood that instead of air, a mixture of air and oxygen or oxygen may be supplied for breathing and cooling purposes and therefore where I use the word "air" I intend to cover any substitute.

I claim:

1. A device of the character described comprising a mask or shield of strong light material shaped into a nose piece having laterally-extending wings to cover the eyes and cheek bones of a wearer, lenses in the mask or shield on opposite sides of the nose piece, a member adapted to fit upon the head of a wearer, and a hinged connection between said member and said mask or shield at a point permitting the mask or shield to be swung up and rest upon the top of the head of a wearer and also to be swung down and be held by gravity in front of the face.

2. In a device of the character described, a mask or shield of strong light material shaped to fit over the upper portion of the face of a wearer, a continuous cushion on the rear side of the mask or shield of the size and shape to extend across the forehead down the cheeks and across the upper lip of a wearer, and means for supporting the mask or shield upon the head so as to permit it to be swung up and rest upon the top of the head, and also to be swung down and be held by gravity in front of the face with the cushion engaging with the face.

3. A device of the character described comprising a shield or mask of strong light material shaped to extend across the upper portion of the face of a wearer, a continuous cushion on the rear side of the mask or shield adapted to extend across the forehead down the cheeks and across the upper lip of a wearer, means for supporting the mask or shield on the head of the wearer so as to permit the cushion to be pressed against the face of the wearer by the weight of the mask or shield, and an air-supply conduit connected to the shield and opening into the space behind the same bounded by the annular cushion.

4. A device of the character described

comprising a shield or mask of strong light material shaped to extend across the upper portion of the face of a wearer, a continuous cushion on the rear side of the mask or shield adapted to extend across the forehead down the cheeks and under the nose of a wearer, means for supporting the mask or shield on the head of the wearer so as to permit the cushion to be pressed against the face of the wearer by the weight of the mask or shield, and an air-supply conduit connected to the shield and opening into the space behind the same bounded by the cushion, lenses in the mask or shield in position to register with the eyes of the wearer, and there being long narrow slots in the mask or shield in the vicinity of the exterior of the lenses for the purpose of permitting air under pressure to flow across the outer faces of the lenses and keep them clean.

5. A device of the character described comprising an adjustable head band, and a mask or shield hinged at the upper rear corners to the head band, the mask or shield being shaped to cover the upper portion of the face of the wearer and having a central section shaped to cover the nose of the wearer and laterally-extending rearwardly-curved wings, and lenses arranged in the wings on opposite sides of the nose section, the parts being so constructed and arranged that the mask or shield may be swung up upon the head of the wearer and also be swung down in front of the face and be held down by gravity.

6. In a device of the character described, a mask or shield of strong light material shaped to fit over the upper portion of the face of the wearer, lenses in the mask or shield in position to align with the eyes of the wearer, and means for producing currents of air across both faces of the lenses.

7. A device of the character described comprising a mask or shield of strong light material shaped into a nose piece having laterally-extending wings to cover the eyes and cheek bones of a wearer, lenses in the mask or shield on opposite sides of the nose piece, an adjustable cap adapted to fit upon the head of a wearer, a hinged connection between said cap and said mask or shield at a point permitting the mask or shield to be swung up and rest upon the top of the head of a wearer and also to be swung down and be held by gravity in front of the face, and deep skirts depending from the cap.

8. A device of the character described comprising a shield or mask of strong light material shaped to extend across the upper portion of the face of a wearer, a continuous cushion on the rear side of the mask or shield adapted to extend across the forehead down the cheeks and across the upper lip of a wearer, a cap adapted to be worn on the head, means for supporting the mask or

shield from the cap so as to permit the cushion to be pressed against the face of the wearer by the weight of the mask or shield, an air-supply conduit connected to the shield 5 and opening into the space behind the same bounded by the cushion, and deep skirts depending from the cap.

9. A device of the character described comprising a mask or shield of strong light 10 material shaped into a nose piece having laterally-extending wings to cover the eyes and cheek bones of a wearer, lenses in the mask or shield on opposite sides of the nose piece, a member adapted to fit upon the head of a 15 wearer, and a hinged connection between said member and said mask or shield at a point permitting the mask or shield to be swung up and rest upon the top of the head of a wearer and also to be swung down in 20 front of the face.

10. In a device of the character described, a mask or shield of strong light material shaped to fit over the upper portion of the face of a wearer, a continuous cushion on 25 the rear side of the mask or shield of the size and shape to extend across the forehead down the cheeks and across the upper lip of a wearer, and means for supporting the mask or shield upon the head so as to permit it to 30 be swung up and rest upon the top of the head and also to be swung down and be held in front of the face with the cushion engaging with the face.

11. A device of the character described 35 comprising a shield or mask of strong light material shaped to extend across the upper portion of the face of a wearer, a continuous

cushion on the rear side of the mask or shield adapted to extend across the forehead down the cheeks and across the upper lip of a 40 wearer, means for supporting the mask or shield on the head of the wearer so as to permit the cushion to be pressed against the face of the wearer, and an air-supply conduit connected to the shield and opening 45 into the space behind the same bounded by the cushion.

12. In a device of the character described, a mask or shield of strong light material shaped to fit over the upper portion of the 50 face of a wearer, a continuous cushion on the rear side of the mask or shield of the size and shape to extend across the forehead, down the cheeks and over the upper lip of a 55 wearer, lenses in said mask or shield, and means for holding the mask or shield against the face of a wearer.

13. A device of the character described comprising a mask or shield of strong light material shaped into a nose piece having laterally-extending wings to cover the eyes and cheek bones of a wearer, lenses in the mask or shield on opposite sides of the nose piece, and means for supporting the mask or shield 60 upon the head of the wearer so as to permit it to rest on top of the head and also to be 65 swung down in front of the face.

In testimony whereof, I sign this specification in the presence of two witnesses.

JAMES T. BRAYTON.
